The ornamental design of the combined electrical plug and safety adapter, as shown and described herein.

DESCRIPTION

FIG. 1 is a rear and upper right perspective view of a combined electrical plug and safety adapter showing my new design;

FIG. 2 is a left side elevational view of a combined electrical plug and safety adapter showing my new design on an enlarged scale, the right side elevational view being a mirror image;

FIG. 3 is a top plan view thereof, the bottom plan view thereof being a mirror image;

FIG. 4 is a front end elevational view thereof;

FIG. 5 is a rear end elevational view thereof; and, FIG. 6 is a rear and upper right perspective view of a combined electrical plug and safety adapter showing my new design with the protective cover in the retracted position and on the same scale as FIG. 1.

FIG.1.

FIG.2.

FIG.3.

FIG.4.

FIG.5.

FIG.6.
